UNITED STATES PATENT OFFICE.

CHARLES F. ALBERT, OF PHILADELPHIA, PENNSYLVANIA.

MUTE FOR STRINGED INSTRUMENTS.

SPECIFICATION forming part of Letters Patent No. 335,872, dated February 9, 1886.

Application filed October 19, 1885. Serial No. 180,331. (No model.)

To all whom it may concern:

Be it known that I, CHARLES F. ALBERT, a citizen of the United States, residing in Philadelphia, Pennsylvania, have invented an Improved Mute for Stringed Instruments, of which the following is a specification.

My invention consists of an improved mute for the violin, viola, violincello, or similar stringed instrument, as fully described and 10 claimed hereinafter.

In the accompanying drawings, Figure 1 is a face view illustrating my attachment applied to the bridge of a violin. Fig. 2 is a side view of the same. Fig. 3 is a sectional view. Fig. 15 4 is a view similar to Fig. 1, illustrating a further improvement. Fig. 5 is a similar view of a modification. Fig. 6 is a side view corresponding to Fig. 5. Fig. 7 is a side view corresponding to Figs. 5 and 6, embodying a 20 further improvement; and Fig. 8 is a perspective view of one form of my improvement detached from the bridge of the instrument.

Referring to Figs. 1, 2, and 3, A is the ordinary bridge, over which pass the strings *a* of 25 the instrument.

Mutes of the ordinary construction, as applied to the bridge of a violin or similar instrument, extend but a limited distance above the top of the bridge, the main portion being 30 in the form of legs, which embrace the bridge itself; but I have found that by constructing a mute which shall have its upper portion extend above the bridge to a length equal or nearly equal to the height of the bridge itself 35 a much more uniform and pleasing quality of tone can be obtained than with a mute of the ordinary form. Thus it will be seen on reference to Figs. 1, 2, and 3 that the legs *b* of the mute B, which embrace the bridge, are 40 comparatively short, while the body of the mute extends above the top of the bridge to a length equal or nearly equal to the height of the bridge itself.

In order to still further improve the quality 45 of tone obtained with my improved mute, I cut the bottom of the groove, by which the legs *b* are formed, on a curve, *x*, Fig. 3, corresponding with the curve of the top of the bridge, the mute thereby becoming a more integral part of the bridge, to vibrate with it

under the action of the strings. In mutes of the ordinary construction the bottom of this groove in the mute is usually straight, so that it cannot rest on the top of the bridge at more than one point, whereas in my device the mute 55 has a firm bearing on the top of the rest throughout its width, except where the notches occur for the passage of the two central strings, as shown in Fig. 3. The upper part of the mute B, I have shown in the drawings as in the 60 form of a flat plate, which may be in one piece with or may be attached to the portion which carries the legs *b*, or of which the legs are formed.

Where it is desired to still further soften the 65 tone, or, in other words, to increase the action of the mute, the detachable piece D, Figs. 4 and 7, may be applied to the upper plate portion of the mute proper. This detachable piece D may be in the form of a solid or hollow sphere, Fig. 4, or flattened ball, Fig. 7, with a slit or groove for the reception of the plain portion of the mute proper. This detachable piece D has the effect of lessening the vibrations, and I prefer to make it of some 70 such material as hard rubber, papier-maché, or wood. Its shape may be varied to suit the user; but I prefer to make it of the flattened form shown in Fig. 7.

For convenience I prefer to use the upper 80 part of the mute as a string-gage, the top edge and side edges of the plate above the bridge forming convenient points for the notches to test the different strings.

In the drawings I have illustrated a construction of gage for which I have applied for patent December 12, 1885, Serial No. 185,497.

Where it is desired to make the mute and gage above described in more economical form, I may stamp it all out of sheet metal, with 90 three legs, *b b b'*, the third leg, *b'*, being bent, so that when applied to the bridge it will be on one side thereof, while the two legs *b b* are on the other side, as shown in Figs. 5, 6, and 7.

I claim as my invention—

1. A mute for a violin or other instrument, having its portion which extends above the bridge equal or nearly equal in length to the height of the bridge.

2. A mute for a violin or similar instru- 100

ment, having the bottom of the slot between the legs which embrace the bridge on a curve corresponding with the top of said bridge.

3. A mute for a violin or similar instrument, having a detachable piece, D, substantially as and for the purpose set forth.

4. A mute for a violin or similar instrument, having in its upper part a gage for the strings of the instrument, substantially as set forth.

In testimony whereof I have signed my name to this specification in the presence of two subscribing witnesses.

C. F. ALBERT.
